Specification for Design.

Patented Jan. 23, 1917.

Application filed June 17, 1916. Serial No. 104,284. Term of patent 3½ years.

To all whom it may concern:

Be it known that we, FRANK L. MACKEMER and ELI M. MACKEMER, citizens of the United States, and residents, respectively, of Peoria, in the county of Peoria and State of Illinois, and Galesburg, county of Knox, and State of Illinois, have jointly invented a new, original, and ornamental Design for Automobile-Bodies, of which the following is a specification, reference being had to

the accompanying drawing, forming part thereof.

In the accompanying drawings, Figure 1 is a perspective view, and Fig. 2 is a top plan together showing our new design.

We claim:

The ornamental design for an automobile body, as shown.

FRANK L. MACKEMER.
ELI M. MACKEMER.
